US00D942542S

(12) **United States Design Patent** (10) **Patent No.:** **US D942,542 S**
Hyun et al. (45) **Date of Patent:** **** Feb. 1, 2022**

(54) **ELECTRONIC WHITEBOARD**

(71) Applicant: **LG Electronics Inc.**, Seoul (KR)
(72) Inventors: **Joe Hyun**, Seoul (KR); **Yongho Lee**, Seoul (KR); **Jiyeon Lee**, Seoul (KR); **Hyeyoung Hong**, Seoul (KR)
(73) Assignee: **LG ELECTRONICS INC.**, Seoul (KR)
(**) Term: **15 Years**
(21) Appl. No.: **35/509,671**
(22) Filed: **Dec. 23, 2019**
(80) **Hague Agreement Data**
Int. Filing Date: **Dec. 23, 2019**
Int. Reg. No.: **DM/205930**
Int. Reg. Date: **Dec. 23, 2019**
Int. Reg. Pub. Date: **Jun. 26, 2020**

(30) **Foreign Application Priority Data**

(57) **CLAIM**

The ornamental design for an electronic whiteboard, as shown and described.

DESCRIPTION

1. Electronic whiteboard

1.1 : Perspective

1.2 : Front

1.3 : Back

1.4 : Left

1.5 : Right

1.6 : Top

1.7 : Bottom

1.8 : Back perspective view

1.9 : Partial view of the lower left front portion of the electronic whiteboard in a condition of use with the cover in an open position

1.10 : Perspective showing the electronic whiteboard with environment

1.11 : Perspective showing the electronic whiteboard in a rotated position with environment

The broken lines are just for illustrative purposes and do not form any part of the claimed design.

1 Claim, 11 Drawing Sheets
